HALVER R. STRAIGHT, OF ADEL, IOWA.

BUILDING-BLOCK FOR DOOR-JAMBS.

1,191,364.

Specification of Letters Patent. Patented July 18, 1916.

Application filed November 6, 1912. Serial No. 729,912.

To all whom it may concern:

Be it known that I, HALVER R. STRAIGHT, a citizen of the United States, residing at Adel, in the county of Dallas and State of Iowa, have invented a certain new and useful Building-Block for Door-Jambs, of which the following is a specification.

The object of my invention is to provide a building block that may be readily and easily made of vitrified clay or the like and produced by means of the ordinary tile making machines provided with suitable dies, whereby the blocks may be formed complete ready for burning; and further to provide a building block of this kind that may be readily and easily set in position at the sides of an opening in a building, and when so set the building block itself will form a mold to receive cement or the like which cement may enter and fill the building block and also the adjacent portions of ordinary hollow tile blocks used for making walls to thereby form a completed structure in which nothing is visible from the exterior except the vitrified tile, and at the same time the walls and door frames will be firmly and rigidly united and held in place and reinforced by the concrete or other material within the hollow tile.

A further object is to provide a frame of this kind that may be readily, quickly and easily shaped by the operator who is constructing the building so that the frame tile may be adapted for use in connection with hollow tile walls of different thicknesses.

A further object is to provide a building block of this class that may be readily and easily shaped to receive cross braces also made of hollow tile and designed to be permanently united with the tile frame members by means of a filling of cement or the like, and at the same time forming a mold for receiving the cement and for uniting said cross braces permanently to the sides of the door frame.

A further object is to provide a building block of this class that may be readily and easily adapted for forming the sides, top and bottom of a window frame for a wall made of hollow tile.

A further object is to provide a building block for door frames especially designed to be used in connection with the door frames of buildings such as silos, and in this connection it is my object to provide

a building block especially designed to contact with an ordinary silo door for the purpose of forming a substantially air-tight joint between the door and the building block; and also in this connection to provide a building block which may be used interchangeably on either side of a door frame and which is also adapted to receive and support a window or door frame, made of wood or other material, on the interior of the tile door frame.

My invention consists in certain details, in the construction, arrangement and combination of the various parts of the device, whereby the objects contemplated are attained, as hereinafter more fully set forth, pointed out in my claims and illustrated in the accompanying drawings, in which:

Figure 1 shows an end elevation of a building block embodying my invention. Fig. 2 shows a detail, horizontal, sectional view on the line 2—2 of Fig. 3. Fig. 3 shows a front elevation of a part of a building such as a silo having a door opening therein embodying my improvements and having parts broken away to show the manner in which the cross braces and side members of the door frame are filled with concrete and reinforced by wires or rods. Fig. 4 shows an enlarged, detail, sectional view on the line 4—4 of Fig. 3. Fig. 5 shows an enlarged, detail, perspective view of one end of a tile embodying my invention showing a part of the inner side of the block removed to receive the tile cross braces. Fig. 6 shows a detail, perspective view of the modified form of my invention illustrating beveled ends for forming rectangular window frames, and Fig. 7 shows a side elevation of a part of a building having a rectangular window frame placed therein, the building blocks for the frame being provided with beveled ends, as shown in Fig. 6.

Referring to the accompanying drawings, it is obvious that my improvement can be manufactured from clay by the use of the same machines as are ordinarily employed in making hollow tile, it being understood of course that a suitable die or former is used in connection with such machines. The completed building block after having been shaped in a machine of this kind is then burned or vitrified in the ordinary manner.

The building block which embodies my invention comprises two straight side walls 10, a straight inner face member 11, an

outer face member 12 and a central bracing member 13. At the ends of the inner face member 11 two shoulders 14 are formed and in each shoulder is a recess 15 for purposes 5 hereinafter made clear. In the outer face member 12 two longitudinal notches 16 are formed, extending from the exterior to a point slightly spaced apart from the interior of the outer face member 12 so that an 10 operator may readily and easily break out the central portion of the outer face member between these notches. The distance to which these notches can be spaced apart, when the tile is made, can be varied to suit 15 the requirements.

The reference numeral 17 is used to indicate ordinary hollow tile building blocks designed to be used in connection with my improved door frame building blocks.

20 The numeral 18 indicates an ordinary hollow tile block designed to be used for forming cross braces between the sides of a window frame made of my improved building blocks.

25 My improved building blocks are especially designed to be used in connection with structures such as silos and when so used the building may be erected or constructed as follows: First, the building walls are 30 made of ordinary hollow tile and suitable openings left therein for the door frame, then the operator who is constructing the building breaks out of each of the building blocks that form the door frames so much of 35 the outer wall member 12 as is necessary to permit the door frame members to receive the adjacent portions of the walls of the building. This may be readily and easily done by breaking the material forming my 40 improved building blocks along the proper ones of the notches 16. Then my improved building blocks are placed in upright positions with the adjacent ends of the building blocks that form the walls inserted into the 45 outer portions of the door frame blocks through the opening made by the removal of the parts broken away along the notches 16. The manner in which the wall blocks are admitted into the frame blocks is illustrated in Figs. 2 and 3. Obviously the operator need not exercise great care and skill 50 in having the ends of the wall building blocks made smooth and even for the reason that all of these ends are concealed by the 55 door frame building blocks and the openings therein are also covered by the door frame building blocks. When one or more of the door frame building blocks are thus placed in position the structure is strengthened, reinforced and the parts firmly united 60 by pouring into the upper ends of the door frame building blocks a quantity of concrete in such condition that it will entirely fill the door frame building blocks and flow 65 out a short distance into the adjacent por-

tions of the wall building blocks, as shown in Fig. 3.

At the point where it is desired to provide cross braces for the door frame, the operator cuts away from the inner member 11 70 near the top a small portion of said member, as illustrated in Fig. 5. He then places a hollow tile cross brace 18 in position projecting through the inner part of the door frame member, as illustrated in Fig. 3. Then 75 suitable binding or reinforcing wires or rods 19 are extended through the cross brace member 18 and through the door frame members into the blocks forming the wall members and then the cross brace member 80 18 may be filled with concrete material to break the small opening through the top wall thereof so that the entire interior of the cross brace member and the adjacent portions of the door frame members and wall 85 members may be filled with cement, thus securely tying the binding or reinforcing wires in position and thoroughly bracing and connecting all of these parts. The next 90 door frame members that are placed above 95 the cross brace member are then broken away at their lower inner portions so that they may fit over the top half of the cross brace member 19, as illustrated in Fig. 4, so that when completed the exposed portions 100 of the entire structure are all of vitrified tile, and although all of the portions adjacent to the door frame structure are reinforced by solid cement or concrete, none of these is exposed and therefore a very neat and finished appearance to the structure is provided.

By having the shoulders 14 on the inner face of the door frame blocks, I provide for forming a substantially air-tight joint with 105 an ordinary silo door which is placed in position from the interior of the structure, as shown in Fig. 2, the door being indicated by the numeral 20. The door rests against the shoulder 14 and is held firmly in position by 110 the pressure of the ensilage or other material within the silo. If desired the groove 15 may be used to receive a packing material such as soft rope to aid in forming a tight joint.

115 In the modified form of my invention illustrated in Figs. 6 and 7, I have beveled the end portions of the building block at 21, and thus a rectangular window frame may be made of these blocks alone in the manner 120 illustrated in Fig. 7 with the adjacent portions of the wall on all sides admitted into the window frame blocks, and the parts may all be united and braced by filling the window frame blocks and the adjacent portions 125 of the wall blocks with cement in the manner described.

In a building block of this kind that is 130 made of vitrified clay, it would be impracticable to wholly remove a portion of the outer

face of the building block when the building block is being originally made for the reason that the adjacent sides would then be unsupported and when subjected to the intense heat required for vitrifying the side walls would not retain their proper shape; therefore when building blocks are made, according to my invention, of such material as vitrified clay, the outer face member must be left in position until after the material has been vitrified.

In practice it has been found very easy for an operator, when constructing a building, to remove such portions of the outer wall member as he may desire and as may be required to fit the wall at the time the building is being constructed.

I claim as my invention:

1. A building block formed of vitrified clay, and comprising parallel sides, an inner member, a convex outer member, the said inner member being narrower than the distance between the parallel sides to form shoulders, the outer member being provided with longitudinal notches, for the purposes stated.

2. In a building block for forming frames of openings in buildings comprising side walls parallel to each other, a longitudinal partition between said members and perpendicular to the inner and outer wall members, said inner wall members having longitudinal

slots opposite the inner edges of said side members, and the outer members being provided with longitudinal shoulders to receive a door, and longitudinal grooves in each of said shoulders.

3. A building block formed of vitrified clay, and comprising parallel sides, an inner member, a convexed outer member, a central partition between the side members, the said inner member being narrower than the distance between the parallel side to form shoulders, the said shoulders being provided with longitudinal grooves, and the outer member being provided with longitudinal notches for the purposes stated.

4. In a building block for forming frames of openings in buildings, comprising parallel sides, an inner member, an outer member, a longitudinal partition between and parallel to said inner and outer members, said outer wall member having longitudinal slots opposite the edges of said side wall members, the inner member being contracted opposite the adjacent edges of said side wall members to form shoulders, said shoulders being provided with mitered ends.

Des Moines, Iowa, October 7, 1912.
